UNITED STATES PATENT OFFICE.

JOHN GORDON, OF CHICAGO, ILLINOIS.

THERMOSTATIC-CONTROLLED VALVE.

Application filed January 25, 1927. Serial No. 163,500.

The present invention is directed to improvements in thermostatic controlled valves.

The primary object of the invention is to provide a device of this character so constructed that should the flame of the pilot burner become extinguished the supply of gas will be instantly cut off from the pilot burner and heater burner.

Another object of the invention is to provide a device of this kind which will be extremely simple in construction and sensitive in operation, and one which will quickly and positively operate to open or close the fluid flow controlling valve.

In the accompanying drawings:

Figure 1 is a vertical sectional view through the valve, showing the valve stems in its elevated position to permit gas to flow freely to the burner.

Figure 2 is a sectional view on line 2—2 of Figure 1.

Figure 3 is a side view of the valve showing the modified form of the invention.

Figure 4 is a sectional view on line 4—4 of Figure 3.

Referring to the drawings, 1 designates a vertically disposed casing in which are formed vertically spaced webs 2 and 3, provided, respectively, with valve seats 4 and 5, said casing having branches 6 and 7 connected therewith. A gas inlet or supply pipe 8 is connected with the branch 6, while to the branch 7 is connected a pipe 9 which supplies the fuel to the burner or burners, not shown.

The upper end of the casing is provided with a stuffing box 10 having mounted thereon anti-friction roller bearings 11 which engage the stem 12, said stem being slidably in the box 10 and has adjustably mounted thereon valves 13 and 14 which coat, respectively, with the seats 2 and 3. The lower end of the stem engages the upper end of the spring 15 mounted upon the bottom of the casing and below the valve seat 3, said spring serving to normally hold the stem elevated and the valves unseated in order that gas can flow freely through the casing as long as the burner is in operation. The upper end of the stem 12 is provided with an enlargement 16 having a transverse groove 17 formed therein, the purpose of which will be later explained.

Mounted upon the top of the casing is a frame 18, the top bar 19 of which is provided with a threaded opening 20 and in which is

threaded for adjustment the stem 21, said stem having an enlargement 22 formed upon its lower end and is provided with a transverse groove 23 which confronts the groove 17 of the enlargement 16, said grooves when confronting providing a guide 24 for co-operation with the head 25, said head having oppositely disposed tapered ends 26 and 27. Leading from the casing 1 at a point below the valve seat 5 is a horizontally disposed pipe 28, the outer end of which has fixed thereto the lower end of the pipe 29, the orifices 30 in its upper end constituting a pilot burner. The pipe 28 is provided with a valve 31 which, when open, permits gas to flow through the seat 5 to pass there-through to the pilot burner.

Adjustably mounted upon the pipe 21 is a thermostatic bar 32, the upper end of which is pivotally connected to the outer end of the rod 33, the inner end of said rod being fixed to the head 25.

As shown in Figure 1, the end 27 of the head 25 is in a position to prevent the stem 12 from moving upwardly under the action of the spring 15 and at which time the valves 13 and 14 are unseated, thereby permitting gas to freely flow through the seats to the burner.

As long as the pilot burner is burning, the heat therefrom will maintain the bar 32 in the full line position, as shown in Figure 1. However, if the pilot is extinguished the bar 32 will contract and move to the position shown in dotted lines in Figure 1, thereby drawing the rod 33 inwardly, thus causing the tapered end 27 to move inwardly in the guide 24 formed by the opposed grooves 17 and 23, which action forces the stem 12 downwardly and causes the valves 13 and 14 to seat and close the passages of the seats 4 and 5, thus shutting off the supply of gas to the burner or burners. It will be observed that when the valves 13 and 14 are seated that the spring 15 is compressed, and will remain thus as long as the pilot burner is extinguished. Upon lighting the pilot burner, the bar 32 will expand and move the head 25 forwardly, thus permitting the valves to unseat in an obvious manner.

While I have illustrated the valves 13 and 14 in the preferred form of the invention as seating upon the upper surfaces of the seats 4 and 5 it will be of course understood that they may be so arranged as to seat upon the under surfaces thereof. To

accomplish this it is only necessary that the tapered end 26 of the head 25 enter the guide 24 from the inner end which can be readily accomplished by shortening the bar 33.

5 In the modified form of the invention as shown in Figures 3 and 4, a bracket 34 is mounted upon the casing 35 and pivotally supports the upper end of the link 36, the lower end of which is pivotally connected to the upper end of the link 37 by a pin 38. The lower end of the link 37 is pivoted to the upper end of the valve stem 39 which functions in the same manner as the stem 12 of the preferred form of the invention.

10 The rod 40 has its outer end pivoted to the pin 38, while the outer end thereof is similarly connected to the thermostatic-bar 41 mounted in a manner similar to that of the preferred form of the invention. When the rod 40 and links 36 and 37 are in the position shown by dotted lines in Figure 3 of the drawings, the valves 42 and 43 will be unseated, due to the expansion of the 15 bar 41. Should the pilot burner be extinguished, the bar 40 will move to the position shown in dotted lines in Figure 3, thus breaking the links and permitting the spring 44 to move the stem 39 upwardly closing 20 the valves 42 and 43, thus cutting off the supply of gas to the burner or burners.

25 For the sake of clearness I have not deemed it necessary to illustrate the location of the valves with respect to a heater, since it 30 will be of course understood that the same can be connected thereto at any convenient point and in any convenient manner.

Having thus described the invention, I claim:

1. The combination with a valve casing 40 having a seat, a stem slideable in the casing and having a valve for cooperation with the seat, the upper end of the stem having an enlargement thereon, a second enlargement 45 stationarily mounted in alinement with the stem, a head movable between said enlargements and capable of forcing the valve stem downwardly to cause the valves thereof to engage the seat, and thermostatic means for controlling the movement of the head. 50

2. The combination with a casing having vertically spaced valve seats therein for permitting passage of gaseous fuel to a heater burner and pilot burner, a stem slideable in the casing and having valves thereon for cooperation with the respective seats, resilient means for normally holding the stem elevated and the valves unseated, a frame supported by the casing, an enlargement 55 adjustably supported by the frame, a second enlargement carried by the valve stem and alined with the first named enlargement, a head movable between the enlargements and thermostatic means for sliding the head in a direction to force the second enlargement 60 downwardly to seat the valves against the influence of the resilient means to cut off the supply of gaseous fuel to the heater burner and pilot burner, said resilient means unseating the valves when the head is slid 65 in a reverse direction. 70

In testimony whereof I affix my signature.

JOHN GORDON. [L. S.]
